UNITED STATES PATENT OFFICE.

WILLIAM A. COATES, OF CHORLTON-CUM-HARDY, ENGLAND, ASSIGNOR TO WESTINGHOUSE ELECTRIC & MANUFACTURING COMPANY, A CORPORATION OF PENNSYLVANIA.

FLUID-PRESSURE TANK.

Application filed June 4, 1923, Serial No. 643,223, and in Great Britain June 23, 1922.

My invention relates to fluid-immersed electrical devices, and more particularly to means for ventilating the containers for the same.

5 One object of my invention is to provide improved means for venting the space above the fluid in fluid insulated electrical devices.

In accordance with the invention the upper part of the tank of an oil-immersed electrical device, such as a switch, circuit-interrupters or a transformer, is provided with 10 at least two vents which open to the atmosphere at different levels, the lower vent being normally open and provided with a non-return valve which is adapted to close the 15 vent when the pressure within the tank exceeds a predetermined amount and the upper vent being permanently open.

In order that the invention may be more 20 clearly understood and readily carried into practice reference will now be made to the accompanying drawing, which represents by way of example a fragmentary vertical section through the tank of a fluid-immersed circuit-interrupter equipped in accordance with 25 the invention. The fluid generally employed is oil of high grade.

In the form illustrated, the tank cover 1 is provided with vent openings 2 and 3, the 30 former containing a horizontal vent pipe 4 and the latter communicating with an elbow vent pipe 5 adapted to discharge to atmosphere at a higher level than the vent pipe 4. The vent pipe 4 is provided at its inner end with a pivoted flap valve 6, and the pipe 35 5 is provided at its upper end with a cap 7 having lateral discharge openings 8 therein and depending from the center of which is a sphere 9. A liquid receptacle 10, which 40 communicates with the interior of the pipe through drains 11, is formed between the cap 7 and the exterior of the pipe 5.

In operation, the vent pipe 4 is, owing to 45 the inclination of its inner end and the position of the flap valve 6, normally open while the vent pipe 5 is permanently open. When an arc occurs, as upon the opening of the circuit interrupter or upon the occurrence 50 of a short-circuit, a considerable amount of gas is liberated and the increased pressure within the tank causes the valve 6 to close the vent pipe 4, the gases then escaping only

by way of the vent pipe 5. When sufficient gas has escaped to relieve the pressure within the tank to a predetermined extent the 55 weight of the valve 6, which may in some cases be assisted by a spring 12, causes it to fall and open the vent 4 while there is still a stream of gas issuing through the vent 5. This current of gas draws in fresh air 60 through the lower vent by reason of the difference in level between the two vents, this action continues for a sufficient time to ensure that the whole of the upper part of the tank is exhausted of the products of combustion of the oil. 65

It will be apparent that the sphere 9 and cap 7 serve as baffles to prevent oil being projected completely through the vent 5 while the cap 7 serves also to prevent the ingress 70 of moisture while the device is used in an exposed position. In the event of any small quantity of oil being projected through the orifice of the pipe 5 it will be collected in the receptacle 10 and will flow back to the tank 75 through the drains 11.

The invention is not limited in regard to the precise location of the vents and it will be obvious that more than two of such vents may be provided if desired. 80

Although I have described a specific embodiment of my invention, it will be obvious to those skilled in the art that various modifications may be made in the details of construction and arrangement of parts without departing from the principles herein set forth. I desire, therefore, to be limited only to the spirit and scope of my invention, as set forth in the appended claims. 85

I claim as my invention: 90
 1. In an electrical device, the combination with a tank, an insulating fluid in said tank, and an electrical device submerged in said fluid, of venting means for said tank comprising a plurality of vents at different positions and levels, one of said vents being open under all conditions of pressure in said tank, and another of said vents being adapted for closing under predetermined pressure conditions in said tank. 95

2. In an electrical device, the combination with a tank, an insulating fluid in said tank, and an electrical device submerged in said fluid, of venting means for said tank com- 100

prising a plurality of vents at different levels and positions, the vent at the higher level being open under all conditions of pressure in said tank, and another of said vents being adapted for closing under predetermined pressure conditions in said tank.

3. In an electrical device, the combination with a tank, an insulating fluid in said tank, and an electrical device submerged in said fluid, of venting means for said tank comprising a plurality of vents at different levels and positions, the vent at the higher level being open under all conditions of pressure in said tank, and a vent at a lower level being adapted for closing under predetermined pressure conditions in said tank.

4. In an electrical device, the combination with a tank, an insulating fluid in said tank, and an electrical device submerged in said fluid, of venting means for said tank comprising a plurality of vents at different levels and positions, one of said vents being adapted for the release of gases under all conditions of pressure within said tank, and another of said vents being adapted for selectively controlling the admission of air to said tank.

5. In an electrical device, a tank, an insulating fluid in said tank, and an electrical

device submerged in said fluid, said tank being provided with a plurality of vents at different levels, the vent at the higher level being open under all conditions of pressure in said tank, and another of said vents being adapted for closing under predetermined pressure conditions in said tank whereby a stream of air is normally caused to move across the surface of the insulating fluid.

6. The combination with a vertical vent pipe of a cap covering the end of said pipe, perforations opening laterally from the wall of said pipe adjacent said cap, an annular trough on the interior of said cap below said openings, and means for draining said trough into said pipe.

7. The combination with a vertical vent pipe having a reduced diameter at the end thereof, of a cap fitting over the end of said pipe, perforations opening laterally from the wall of said pipe adjacent the end thereof, an annular trough below said openings, means for draining said trough into said pipe, and a member suspended from said cap and adapted to obstruct the opening of said pipe.

In testimony whereof, I have hereunto subscribed my name this 9th day of May, 1923.

WILLIAM A. COATES.
